DOOR LATCH STRUCTURE

Howard J. Murphy, Greenwood, Mass., assignor
to United-Carr Fastener Corporation, Cam-
bridge, Mass., a corporation of Massachusetts

Application April 16, 1936, Serial No. 74,657

6 Claims. (Cl. 70—146)

My invention relates to a latching device of simple and inexpensive construction for use with a door or similar part of a suitable structure.

An object of my invention is to provide a simple, easily manufactured device having a latch means adapted to snap under the action of a spring into a recess or aperture formed in an abutment, the arrangement being such that in order to release the latch for opening the door or the like part, it is only necessary to exert longitudinal pressure on a handle means provided on opposite faces of the part with which the latching device is assembled. Other objects will appear from the following description.

Referring to the drawing, which illustrates a preferred embodiment of my invention:—

Figure 1 is an end elevation of my improved latching device;

Fig. 2 is a plan view of the device shown in Figure 1;

Fig. 3 is a fragmentary side elevation of the device shown in Fig. 2;

Fig. 4 is a side elevation of the device shown in Figs. 1 and 2 with the handle knobs removed;

Fig. 5 is an enlarged section taken on the line 5—5 of Fig. 4;

Fig. 6 is a view similar to that of Fig. 4 but with a side of the outer casing removed showing the parts of my device in latching position;

Fig. 7 is a view similar to that of Fig. 6 but showing the parts in unlatched position;

Fig. 8 is a section taken on the line 8—8 of Fig. 4 with the parts of my device in latching position;

Fig. 9 is a section similar to that of Fig. 8 with the parts in unlatched position;

Fig. 10 is a part sectional view of a latch actuating member used in a preferred form of my device;

Fig. 11 is an enlarged section taken on the line 11—11 of Fig. 10;

Fig. 12 is a section taken on the line 12—12 of Fig. 8 with my actuating member in unlocked position;

Fig. 13 is a section similar to that of Fig. 12 with the actuating member in locked position;

Fig. 14 is a plan view of the slidable latch means used in a preferred form of my device; and

Fig. 15 is a plan view of a spring supporting member used in a preferred form of my device.

Referring in detail to the illustrations, I have shown, in Fig. 2, a casing 1, within which the parts of my latching device are contained, an apertured plate 2 for securing my device to the

proper portion of a door or other part (not shown) with which it is to be assembled, an actuating member 3 extending axially through the casing 1 for moving the latch means of my device, and a knob-like handle 4 secured to each end of the bar 3.

The outer casing 1 may be made of one piece of sheet metal, but, in my preferred form, I have chosen to form it of two pieces, as most clearly shown in Fig. 5. One of the pieces is 10 in the form of a three-sided box-like part 5 having an intermediate wall 6 and spaced side walls 7 upstanding therefrom. The intermediate wall 6 has a screw-receiving aperture 8 and another aperture having a central portion 9, elongations 10 on opposite sides of the central portion, and a slot 11 extending into the material at one side of the central opening 9 between the elongations 10—10 (Fig. 4). The material of the side walls 7—7, adjacent to the outer ends of the elongations 10, is pressed out to form the grooves 10^a extending partially across the width of the walls 7—7, as most clearly shown in Figs. 2, 6 and 7. An end 12 of the casing part 5 is opened to permit passage of the latch means therethrough, 25 as most clearly shown in Figs. 8 and 9. The opposed side walls 7 of the casing part 5 are provided with a flange 13 at one end (Figs. 4 and 6) for securing the casing to the plate 2. The other piece of the casing 1 is in the form of a 30 plate 14 enclosing the open side of the part 5 and having flanges 15 (Figs. 2 and 5) overlying portions of the side walls 7. The plate 14 has a screw-receiving aperture 16 disposed substantially midway of its length (Figs. 8 and 9) 35 and another aperture comprising a central opening 17 and a slot 18 adjacent to the opening 17 (Figs. 6, 7, 12 and 13). The apertures 16, 17 and 18 are disposed in respective opposite relation to the similarly shaped apertures 8, 9 and 11 of the casing part 5. The plate 14 is secured to the part 5 by a means, such as a machine screw 19, extending through the aperture 16 of the plate 14 and the aperture 8 of the intermediate wall 6.

A slidable member 20 is assembled within the casing 1 and adapted to slide longitudinally relative thereto. The member 20 is provided with a latch means comprising a beveled nose 21 adapted to snap under the action of a coil spring 22 into a recess or aperture formed in an abutment (not shown). The spring 22 is assembled within the casing 1 and, in my preferred form, has one end bent in the form of a loop 23 which is hooked around the screw 19, as shown in Figs. 55

6-9. The other end of the spring 22 is slipped over a shank 24 formed as an integral part of a supporting member 25 (Fig. 15) which is shaped to fit within the nose end of the slideable member 20, as most clearly shown in Figs. 6-9. I do not wish to be limited, however, by the particular spring assembly illustrated and described because the form and position of the spring 22 could be changed or alterations made in the particular construction of the spring supporting member 25 without departing from the apparent scope of my invention.

Referring in more detail to the slideable member 20, as illustrated in Fig. 14, I have shown a one-piece sheet metal part comprising a base plate portion 26 and upstanding spaced side walls 27. Each of the free edges of the side walls 27 at one end extend in angular relation to the plane of the plate 26, and the material adjacent to an end of the plate 26 has been bent back in adjacent relationship to the slanting edges of the side walls in a way to form the beveled nose portion 21 (Figs. 8, 9 and 14). An aperture 28 is formed in the plate portion 26 of substantially the shape shown in Figs. 6 and 7 with a portion of the material of the plate 26 extending into the aperture 28 for a predetermined distance to form a projection 29 (Figs. 6 and 7) for a purpose which will be hereinafter more fully described. A slot 30 is formed in each of the side walls 27 and positioned in opposed relation one to another, as most clearly shown in Fig. 14. Each of the slots 30 extends from the longitudinal free edge of one of the side walls 27 to a point adjacent the plate 26. It will be noticed that a free edge of each of the plates 27 adjacent to one side of the respective slot is disposed in an angular relation to the plane of the plate 26 thereby providing the cammed surface 31.

40 In my preferred form, the actuating member 3, as most clearly shown in Figs. 10 and 11, comprises a tube-like outer casing 32 having external threads 33 at opposite ends for cooperating with internally-threaded neck portions of the knobs 4 to secure them to the member after the latching device has been assembled with the part by which it is supported. The outer tube 32 is provided with a rectangular-shaped aperture 34 of predetermined size (Figs. 8, 9, 12 and 13) located in stated position on its length. A pin 35 is driven through the tube 32 and is finally disposed at a predetermined position relative to one end of the aperture 34 in such a way that the free ends project beyond opposite sides of the casing. The free ends of the pin 35 are adapted to engage the cammed surfaces 31 for moving the slideable latch member 20 against the action of the spring 22 in a manner which will be hereinafter more fully described.

60 In order that unlatching of my device may intentionally be prevented, I have provided a locking means as a part of the actuating member 3 which is adapted to cooperate with a part of the casing in such a way that the slideable member 20 cannot be moved when particular parts of my device are in certain respective positions. The parts of my locking means preferably include a rotatable bow-shaped sleeve member 36 positioned within the tube 32 having a rectangular-shaped projection 37 integral with the material of the sleeve at substantially the center thereof and projecting through the aperture 34 of the tube 32, as most clearly shown in Figs. 6-9, 12 and 13. The material at opposite ends 75 of the sleeve 36 is spaced from respective oppo-

site ends of the tube 32 and formed in a way to provide a flat continuous ring 38 (Figs. 10 and 11) with the material of the outside edges of the portions 38 turned inwardly so as to provide a portion 39 enclosing the outer end of the ring. A key-receiving slot 40 is cut in the portion 39 as shown in Fig. 11. A bushing part 41 is located at each of the opposite ends of the tube 32 having one end in substantially adjacent relation to the turned portion 39 of the ring 38 (Fig. 10). The material 42 adjacent to the free ends of the tube 32 is turned inwardly to hold the bushing 41 in secured position. A key-receiving slot 43 extends through the material of each of the bushings 41 (Figs. 3 and 4). 15

In operating the locking means of my device, a key (not shown) is inserted into the slot 43 provided in the bushing located at either end of the tube 32, and the bushing is turned until the slot 43 aligns with the slot 40 at the end of 20 the sleeve 36. At this point, a particularly shaped key is easily inserted into the slot 40 of the sleeve so that the sleeve may be turned so as to move the rectangular projection 37 from a position adjacent the material of the tube 32 25 bordering one longitudinal side of the aperture 34 to a position adjacent the material bordering the other longitudinal side, as most clearly shown in Figs. 12 and 13.

In assembling the parts of my device, the 30 spring 22 and the supporting member 25 are assembled in proper position with the slideable member 20 and the assembled parts are positioned within the casing part 5 so that the latch means 21 faces the opening 12 and the longitudinal free edges of the side walls 7 of the slideable member face the intermediate wall 6 of the part 5. The plate 14 is now moved into position on the open side of the casing part 5 with the flanges 15 overlapping portions of the side walls 40 7. The screw means 19 is inserted through the plate 14, the wall 6, and the intermediate spring loop 23 so that the casing pieces and the parts contained within the casing are in secure final assembly. When the parts have been assembled 45 in the manner hereinabove described, the cammed surfaces 31 will intersect the elongations 10 of the aperture of the intermediate wall 6.

The casing 1 is readily assembled with a door or the like part by forming a hole extending 50 from the surface of that side of the door facing the abutment, when the door is in closed position, into the body portion of the door for a distance equal substantially to the length of the casing. After this has been carried out, a smaller 55 hole is bored through the door in right-angular relation to the first hole and intersecting the first hole at a predetermined point. The smaller hole is adapted to receive the actuating member 3.

As the cross-sectional area of the casing 1 60 is relatively small, the first hole needs to have a diameter which is only slightly larger than the diameter of the casing so that after the casing has been passed longitudinally into the aperture, it will be snugly held in position by 65 the walls surrounding the aperture. It has been found that a round hole provides a suitable setting for securing the casing within the body of the door even though the casing is preferably of a box-like shape. My relatively simple means 70 of assembling the casing part of my device within the door is a great improvement over ordinary methods which required a relatively great amount of time-taking cutting in the door in order to prepare it for receiving a latch device 75

of the type which is now in common use as against my simple device which can be inserted in quickly bored holes.

After the casing 1 has been finally fixed in proper position within the body portion of the door or part with which it is to be assembled, the actuating member 3 is passed through the door and the casing from a point outside one face of the door so that when finally positioned the ends of the member project beyond the front and back of the door in a well known manner. In order to pass the actuating member 3 through the casing, that end of the member on the same side of the pin 35 as the projection 37 is inserted into the central opening 9 of the intermediate wall 6 and as the member is pushed through the casing 1, the projection 37 passes through the slot 11 and the free ends of the pin 35 align with the elongations 10. After the projection 37 is located within the casing 1, a split ring 44 is slipped over the tube 32 and snapped into the peripheral groove 45 cut in the tube 32 on the opposite side of the aperture 34 from the pin 35 so as to engage the outside surface of the plate 14 (Figs. 5 and 8) for preventing complete axial withdrawal of the tube relative to the casing in the direction opposite to that in which it was inserted.

The pin member 35 is now located in a position substantially as shown in Figs. 5 and 8 and when longitudinal pressure is exerted upon the tube 32, so as to move the pin 35 toward the base portion 26 of the slideable member, the opposite ends of the pin 35 engage the cammed surfaces 31 of the slideable member side walls 27 with the result that when the pin has reached the end of the slot 30, as shown in Fig. 9, the nose 21 of the slideable member will have been withdrawn into the casing against the action of the spring 22. When the longitudinal pressure is released, the natural action of the spring 22 forces the latch means 21 into normal engaging position, as shown in Fig. 8, and at the same time the pin 35 returns to the normal position shown in Fig. 8. It will be noticed that when the slideable member is in the position shown in Fig. 9, a portion of the projection 37 extends through the slot 18 of the plate 14 beyond the outside surface of the plate 14. When the latch means 21 is in normal position the projection 37 is disposed entirely within the casing, as shown in Fig. 8. The projection 29 preferably aids in limiting movement of the slideable member by engaging a side of the tube 32, as shown in Fig. 7, after the camming action has been completed.

My latching device may be easily locked so as to prevent movement of the slideable member out of latching position by turning the sleeve 36, as illustrated in Figs. 12 and 13, so that the projection 37 is moved out of alignment with the slot 18. After the projection has been moved out of alignment it will take a position opposite the material of the plate 14 substantially as shown in Fig. 13. As a result of this locking action, it is impossible for the pin member to be moved into engagement with the cammed surfaces 31 for the purpose of changing the position of the slideable member 20. When unlatching is desired, the projection 37 is realigned with the slot 18 thereby allowing the projection to pass part way through the plate 14 when the pin 35 engages the cammed surfaces 31.

As a result of my invention, I have provided a latching device of simple construction compris-

ing a minimum number of parts and capable of easy, yet satisfactory, operation.

Obviously, the mechanical structure of my latch device might be widely varied without departing from the principles exemplified by this disclosure and for that reason I do not wish to be limited by the preferred form of my invention as illustrated and described because the scope of my invention is best defined in the following claims.

I claim:

1. A door latching device comprising, in combination, an outer casing having opposed apertured sides, a spring-actuated member slidably disposed within said casing, said member having a base plate facing one of said sides and upstanding spaced side walls integral with said base plate, said plate having an aperture in alignment with the apertures of said sides, said member having a latch means at one end thereof and a cam surface formed in one of said side walls, and a member extending axially through the apertures of said casing and said base plate, said last-mentioned member having means engaging the cam surface of said side wall when pressure is applied longitudinally of said axially-extending member thereby moving said slideable member for disengaging said latch means from a cooperating recess of another part, and a stop means formed in said plate portion cooperating with said axially-extending member for limiting longitudinal movement of said slideable member relative to a side of said casing.

2. A door latching device comprising, in combination, an outer casing having a pair of opposed apertured sides, a spring-actuated member slidably disposed within said casing and having a latch means at one end thereof, said member having a base plate facing one of said sides and upstanding spaced side walls integral with said base plate, said plate having an aperture in alignment with the apertures of said sides, said side walls having oppositely disposed slots extending from the longitudinal free edge of each of said side walls to a point adjacent said base plate, the free edge of the material adjacent to one side of each of said slots disposed in angular relation to said base plate for providing camming surfaces, and a member extending axially through the apertures of said casing and said base plate, said last-mentioned member having means engaging the cammed surfaces of said side walls when pressure is applied longitudinally of said axially-extending member thereby moving said slideable member for disengaging said latch means from a cooperating recess of another part.

3. A door latching device comprising, in combination, an outer casing having a pair of opposed sides, each of said sides having an oppositely disposed central opening with a slot on one side thereof, a spring-actuated member slidably disposed within said casing, said member having a latch means at one end thereof normally disposed in relative latching position, said member having a base plate facing one of said sides and upstanding spaced side walls integral with said base plate, said plate having an aperture in alignment with the opening and slot of each of the sides of said casing, at least one of said side walls having a cam surface, and a tube-like member extending axially through the central openings of said sides and the aperture of said base plate, said last-mentioned member having a projecting means engaging said cam surface when pressure is applied longitudinally of

5 said tube-like member thereby moving said slide-
able member for disengaging said latch means
from a cooperating recess of another part, and
said tube-like member having a movable locking
means adapted to project through the slot adja-
cent to the opening of one of said casing sides
when said projecting means is in engagement
with said cam surface and means for turning
the locking means out of alignment with said
10 slot when said means is out of engagement
with said cam surface thereby to lock said slide-
able member in latching position.

15 4. A door latching device comprising an aper-
tured outer casing, a spring-actuated slideable
member disposed within said casing having a
latch means at one end thereof, said slideable
member having at least one cam surface, and a
member extending axially through said casing
20 for moving said slideable member for disengaging
said latch means from a cooperating recess of
another part, said last-mentioned member having
a means projecting from at least one side
thereof for engaging said cam surface when
pressure is applied longitudinally of said mem-
ber, and said last mentioned member having an
25 aperture and a movable locking means extend-
ing through said aperture, said locking means
adapted to be disposed in one position for align-
ment with an aperture of said casing and in an-
30 other position out of alignment with said
aperture.

35 5. A door latching device comprising an aper-
tured outer casing, a spring-actuated slideable
member disposed within said casing having a
latch means at one end thereof, said slideable
member having a cam surface, and a member
extending axially through said casing for moving

5 said slideable member for disengaging said latch
means from a cooperating recess of another
part, said last-mentioned member having an
apertured tubular part, a means extending from
said part for engaging said cam surface when
pressure is applied longitudinally of said part,
and a rotatable sleeve disposed within said part
having a projecting means extending through
said aperture, said sleeve adapted to be turned for
moving said projecting means out of alignment
10 with a cooperating aperture of said casing there-
by locking said device for preventing disengage-
ment of said latch means, and means assembled
with said tubular part preventing unintentional
complete removal thereof from said casing. 15

15 6. A door latching device comprising an aper-
tured outer casing, a spring-actuated slideable
member disposed within said casing having a
latch means at one end thereof, said slideable
member having at least one cam surface, and a
20 tubular member extending axially through said
casing for moving said slideable member for dis-
engaging said latch means from a cooperating re-
cess of another part, said tubular member hav-
ing a pin projecting from opposite sides thereof
25 for engaging said cam surface when pressure is
applied longitudinally of said member, an aper-
ture located between said pin and one of the ends
of said tubular member and in stated position
relative to the free ends of said pin, and a mov-
able locking means extending through said aper-
ture, said locking means adapted to be disposed
in one position for alignment with an aperture
of said casing and in another position out of
30 alignment with said aperture. 35

HOWARD J. MURPHY.
